ATTORNEYS.

UNITED STATES PATENT OFFICE.

GEORGE F. KNAPP, OF ST. LOUIS, MISSOURI.

FOLDING BARREL.

SPECIFICATION forming part of Letters Patent No. 312,475, dated February 17, 1885.

Application filed July 2, 1884. (Model.)

To all whom it may concern:

Be it known that I, GEORGE F. KNAPP, a citizen of the United States, residing at St. Louis, in the State of Missouri, have invented 5 certain new and useful Improvements in Folding Barrels, of which the following is a description.

This invention relates to that class of devices by means of which barrels are reduced to a knockdown compact condition for return after service; and its object is to provide means whereby the center of a barrel may be securely held, while either end is adapted to be opened to examine the contents, and means 15 whereby the hoops may be locked securely, or readily unlocked.

To this end my invention consists in the construction and combination of parts forming a folding barrel, hereinafter described 20 and claimed, reference being had to the accompanying drawings, in which—

Figure 1 is a perspective view of part of a barrel showing my invention. Fig. 2 is an end view of the same in a knockdown condition without the heads. Fig. 3 is an end elevation of two segments of barrel-staves and the lock therefor. Fig. 4 is a detail view of the central hoop-coupling, and Fig. 5 is a detail view along the hinge-joint of the barrel. 25 *a* represents a series of staves forming a half of a barrel by being secured upon half-hoops *c c c*, and *b* represents the other half of the barrel similarly formed and secured upon other half-hoops *D*, which are hinged to the 30 hoops *c* by links *C*. The central hoop is provided with a link, *d*, at one end, and with a hook, *e*, at the other end, adapted to engage each other; but to bring them together requires a peculiar construction and combination 35 of the parts, because when the edges of the two halves *a* and *b* are together the link *d* cannot be engaged with or disengaged from the hook *e*. This is to prevent the barrel being knocked down accidentally when its ends are 40 removed for examining the contents. I place the hinge-joint of the link *d* and hoop *c* projecting slightly over the edge of the half-barrel *a*, in order that the link may swing down to engage the hook when the half-barrel *b* is

slid under the half *a*, as seen in dotted lines 50 in the section at Fig. 4.

To adapt the half *b* to so slide under the part *a*, I place the hook *e* back from the edge, leaving a space, *B*. By this means the hook and loop may be engaged and then the half *b* 55 be crowded back in place in front of the half *a*, forming a very tight fit, and one that cannot be knocked down otherwise than by the process designed for that purpose.

In order that the barrels may be quickly 60 opened at their ends for inspection, I provide the end loops with locks, consisting of links *f*, hinged or loosely hung to the half-hoops *D*, and adapted to engage a shoulder, *g*, on lugs *h*, which are secured to the half hoops *c* at the 65 ends of the barrel.

To draw the ends of the barrel together, I provide levers *A*, hinged to the lugs *h* in front of and near the top of the shoulders *g*. These levers are of a thickness sufficient to bring 70 their rear faces as far from the center of their pivots as the shoulders *g*, so that by inserting the end of a lever in a loop and drawing back on the lever it will gradually bring the link over behind the shoulder *g*, where the link will 75 hang very firmly until forcibly disengaged.

To disengage the link, I provide the lever with an angular toe, *i*, which prys under the link and raises it free of the shoulder when the lever is pushed forward. This toe is so 80 formed as to engage the link while the latter is engaged with the shoulder *g*, thus holding the lever down upon the barrel.

The hinge *C* permits the two halves of the barrel to fold back upon themselves outside 85 to outside, so as to be packed solid for transportation. The barrel is thus made convenient for use, and is readily reduced to form for economical shipment.

What I claim as my invention, and desire 90 to secure by Letters Patent, is—

1. The combination, in a folding barrel, of two sets of staves forming halves of a barrel secured to two parts of a hoop hinged together, a link loosely hung to one part of the hoop 95 at the edge of one half of the barrel, and a hook permanently secured to the other half of the barrel at a distance from the edge thereof

corresponding to the length of the link, substantially as described, whereby the two parts of the barrel will be held firmly together when the staves are in the same plane, and whereby 5 the staves may be thrown out of plane, the one to pass over the other, for the purpose of engagement or disengagement, as set forth.

2. The combination, in a folding barrel, of a lug, *h*, provided with a projecting shoulder, 10 *g*, secured to one part of the barrel, and a link, *f*, hung loosely to the other part, a lever pivoted in the upper portion of the shoulder of the lug, one face of the lever being

as far from the center of its pivot as the corresponding face of the shoulder, and a toe projecting angularly from the said face of the lever, substantially as described, whereby the link may be forced into engagement with the shoulder of the lug, or out of engagement therewith, and whereby the lever may be held down 15 upon the barrel, as set forth.

GEO. F. KNAPP.
